UNITED STATES PATENT OFFICE.

FREDERICK A. STOHLmann, OF BROOKLYN, ASSIGNOR TO GEORGE TIEMANN & CO., OF NEW YORK, N. Y.

STOMACH-PUMP.

SPECIFICATION forming part of Letters Patent No. 340,739, dated April 27, 1886.

Application filed January 2, 1886. Serial No. 187,333. (No model.)

To all whom it may concern:

Be it known that I, FREDERICK A. STOHLmann, of Brooklyn, in the county of Kings and State of New York, have invented a new and useful Improvement in Exhausting and Forcing Apparatus for Stomach-Pumps, &c., of which the following is a specification.

My invention relates to an exhausting and forcing apparatus for stomach-pumps, &c., that is adapted to injecting into the stomach or other place any desired liquid from the receptacle in which it is held, and also to exhausting from the stomach or other place, whatever the contents may be, and discharging the same into a suitable receptacle.

My invention consists of an exhausting and forcing apparatus composed of a suction and forcing bulb of rubber connected to a circular disk or valve base, and having openings and valves working in opposite directions. The rubber tube to be placed into the stomach and the rubber tube to be placed into a receptacle are both connected to a circular disk, and this disk is held against the surface of the aforesaid valve-disk by a central connecting-screw or similar fastening in such manner that if the tube-disk is held in one hand and the forcing-bulb turned by the other hand, or vice versa, a half-revolution, the position of the valves in their relation to the two tubes is reversed, so as to enable the user to inject liquid into the stomach from a basin or receptacle, or to exhaust the contents of the stomach and discharge the same into the basin.

In the drawings, Figure 1 is an elevation, partially in section, of my improved exhausting and forcing apparatus. Fig. 2 is a plan of the upper surface of the valve-disk. Fig. 3 is an inverted plan of the under surface of the valve-disk; and Fig. 4 is a plan of the tube-disk.

A is the rubber exhausting and forcing bulb; B, the valve-base; C, the tube-disk; D, the stomach-tube, and E the tube, upon the end of which is the usual cup, 1, adapted to being placed in a liquid-holding basin or receptacle.

The bulb A and rubber tubes D and E are of the usual character.

The bulb A and valve-base B are firmly con-

nected by wiring or tying the mouth of the former around the periphery of the valve-base.

The valve-base B is preferably made of hard rubber, although other materials—such as metal, celluloid, or wood—might be used, and said base is made with the passage-ways a b through it, and a valve, c, secured to and seated upon the upper surface of the base, and the valve d secured within a valve-chamber in said base and seated against an under surface, 2. •

The valves c and d are preferably secured by screws, so as to be removable, and they operate in opposite directions.

The valve-base B has around its under surface the rim e, and the disk C fits within such rim e and tightly against the surface of the valve-base B, and said parts are connected together by the screw or equivalent device, which will permit of their being turned one upon the other in shifting the position of the valves in relation to the pipes D E. There is a pin, 3, in the circumference of the disk C, and a portion or about one-half of the circumference of the rim e is cut away, forming a notch in which the pin 3 moves to limit the half-revolution of the bulb A and valve-base B. There are tubes g g' projecting from the disk C, to which the tubes D E are connected.

The sides of the bulb A may be marked with the words "Inject" and "Exhaust," accompanied with arrows to denote the direction of flow of the liquid, and in the position shown in Fig. 1 the pump is set to exhaust from the stomach or other place and discharge through the pipe E. By forcing the air from the bulb A through the tube E a partial vacuum is formed, which, upon releasing the bulb, causes the liquid to flow through tube D into the bulb A, and the liquid is ejected through the tube E by squeezing the bulb. If now the bulb A and valve-base B are given a half-revolution, bringing the valve c over the tubes g' and E and the valve d over the tubes g and D, the position and operations are reversed and liquid can be drawn from a receptacle through the tube E into the bulb A, and then forced through the tube D into the stomach.

In place of the bulb A, I might employ a

tubular body and moving piston, similar to a syringe.

My improved exhausting and forcing apparatus or pump is thus available for either operation of forcing liquid into the stomach or other place or of exhausting and discharging its contents, and also for kindred operations and purposes, and the change is made rapidly without disturbing the apparatus.

10 I claim as my invention—

1. The combination, with an exhausting and forcing apparatus, of the tubes and base B and disk C, removably connected to each other, the valves c d upon the valve-base B, and acting in opposite directions, the rim e upon the disk B, and partially removed to form a slot, the pin 3, to limit the movement of one disk

upon the other and determine the position of the valves in relation to the tubes, substantially as specified.

20

2. An exhausting and forcing apparatus having a valve-base and seats and valves working in opposite directions, in combination with a disk and tubes connected therewith, and means, substantially as specified, for connecting the disk to the valve-base, so that the relative positions of the tubes and valves can be reversed, substantially as specified.

25

Signed by me this 28th day of December, A. D. 1885.

FREDK. A. STOHLmann.
